Specification for Design.

Patented Apr. 8, 1913.

Application filed January 11, 1913. Serial No. 741,584. Term of patent 14 years.

To all whom it may concern:

Be it known that I, GROSVENOR N. ALLEN, a citizen of the United States, residing in the city of Oneida, county of Madison, State of New York, have invented a new, original, and ornamental Design for Handles for Spoons, Forks, or Similar Articles, of which the following is a specification, reference being had to the accompanying drawing, which forms part of the same, in which—

Figure 1 is a top view and Fig. 2 is an enlarged partial view somewhat in perspective of the handle of a spoon or fork showing my new design.

I claim:

The ornamental design for a handle for spoons, forks, or similar articles as shown.

GROSVENOR N. ALLEN.
